LOADING MACHINE

Carl J. Watne, Nokomis, Ill., assignor to Sullivan Machinery Company, a corporation of Massachusetts

Application May 7, 1940, Serial No. 333,803

11 Claims. (Cl. 198—9)

This invention relates to loading machines, and more particularly to gathering devices for moving coal or similar material onto the conveyor of a loading machine.

It is an object of this invention to provide an improved loading machine. It is another object of this invention to provide improved gathering means for a loading machine, especially but not exclusively for a loading machine of the track supported and guided type adapted to operate from a mine trackway. It is still another object of this invention to provide improved means for gathering and discharging material onto a loading conveyor and having means for moving said gathering means in an improved manner. Still another object of this invention is to provide an improved material gathering device having improved gathering members and improved means for moving said members to gather and move material onto a conveyor, and then move said members, as they return to gathering position again, in such a way that they will not interfere with the material on the conveyor or tend to pull it off. Still another object of the invention is to provide improved gathering devices which will move material onto a conveyor and then withdraw from their advanced positions to retracted positions without substantially overrunning the forward end of the conveyor. Another and further object of the invention is to provide improved means for substantially preventing escape of material delivered to a conveyor. Other objects and advantages of the invention will, however, hereinafter more fully appear.

In the accompanying drawings there are shown for purposes of illustration one form and a modification which the invention may assume in practice.

In these drawings:

Fig. 1 is a side elevational view of a track mounted loading machine having embodied therein an illustrative form of the improved gathering means.

Fig. 2 is an enlarged plan view of the loading end of the machine of Fig. 1, showing the improved gathering means and a portion of the elevating conveyor.

Fig. 3 is an enlarged vertical sectional view taken on the plane of the line 3—3 of Fig. 2.

Fig. 4 is an enlarged detail sectional view taken on the plane of the line 4—4 of Fig. 2.

Fig. 5 is a cross sectional view taken on the line 5—5 of Fig. 3.

Fig. 6 is a transverse sectional view taken on

the line 6—6 of Fig. 5 and showing one of the gathering devices.

Fig. 7 is a vertical sectional view taken on the line 7—7 of Fig. 6.

Fig. 8 is a perspective view of one of the gathering arms.

Fig. 9 is a perspective view of a modified form of gathering arm.

The illustrative embodiment of the invention 10 is shown incorporated in a loading machine of the track supported and guided type adapted to operate on a mine trackway and generally comprising a main frame or body 1 mounted on wheels 2 adapted to run along a mine trackway 3. It will be obvious that the invention may be 15 incorporated in other types of loaders. Mounted on the main frame 1 is a front elevating conveyor 4 and a rear discharge conveyor 5, and associated with the front elevating conveyor is an improved gathering means generally designated 6. The showing of the loading machine in general is conventional as my invention relates wholly to the gathering devices and elevating or gathering conveyor. The front elevating conveyor 4 and its associated gathering mechanism 6 are pivotally connected at 8 to the forward portion of a horizontally swingable frame 10, and the rear discharge conveyor 5 is 20 vertically adjustable about a pivot 11 at the rearward end of the frame 10. The gathering mechanism 6 gathers the material to be loaded and moves the material across a shovel plate 12 at the forward end of the elevating conveyor 4 and onto a plate 14 extending along the bottom of the conveyor. As will be noted the conveyor mechanism 4 includes a chute or troughlike frame 13 of which the plate 14 forms the bottom, and sloping flanges 14' extending longitudinally of the trough overlie spaces in which flight-moving chains 15 may move. The endless flight-moving chains 15 extend along the sides of the conveyor 4 and pass around guide sprockets 16 attached to a cross shaft 17 arranged at the forward end of the conveyor below the bottom plate 14 with its ends journaled in the sides of a box-like lower portion 18 of the front end of the conveyor frame. The chains 15 are connected by transverse scraper bars 19 which slide along the bottom plate 14 to move the material to be loaded, when the chains are driven by a suitable driving means mounted on the main frame 1, along the conveyor 4 to discharge onto the rear conveyor 5, the latter in turn discharging into a mine car or other suitable receptacle placed beneath the discharge end of the rear conveyor 25 30 35 40 45 50

in a manner well known to those skilled in the art. The plate 14 forming the bottom of the conveyor 4 is arranged in a plane extending parallel to and somewhat below the plane of the shovel plate 12 so that any material moved over the upper edge or lip of the shovel will drop onto the plate 14 and be less likely to be swept off the conveyor by the gathering devices later described. In order to prevent material from sliding down the plate 14 after one bar 19 passes and before another moves up on top of the plate 14, there is provided a suitable gate-like element. This element herein is shown as a piece of flexible material 20 attached in any suitable manner to the lower rearward edge of the shovel plate 12 and resting upon the top of the plate 14 in a position to be lifted by the scraper bars 19 as they pass beneath it during operation of the conveyor. Rubber, reenforced if desired, makes an excellent gate and may be counted on for long 20 life as well as effective sealing.

Referring now in detail to the improved gathering mechanism 6 it will be noted that gathering devices generally designated 21, 21 are mounted on the shovel plate 12, at opposite sides 25 of the forward end of the conveyor trough, to rotate about axes 22 perpendicular to the upper inclined surface of the shovel plate 12. The gathering devices comprise, as shown in Fig. 5, disk-like members 23 attached as by bolts 24 to stub 30 shafts 26 which are journaled in hubs 27 formed on the shovel plate at each side of the conveyor adjacent its lower end. Depending from the disk-like members 23 at the outer edges of the latter and spaced evenly from each other are portions 29 carrying pivot pins 30 to which gathering arms 31 are pivotally connected. Means are provided for rotating the members 23 in such directions that the gathering arms pick up material ahead of the shovel plate and carry it inwardly and upwardly over the upper inclined surface of the shovel plate to the conveyor 4, and this means herein comprises chain sprockets 33 fixed to the lower ends of the stub shafts 26 and having passing around them chains 35 driven by any suitable driving means mounted on the main frame 1. Since the gathering devices are mounted at opposite sides of the conveyor they will, of course, be rotated in opposite directions. As shown in Fig. 2, the gathering arms 31 are so constructed and arranged that they will in alternation extend beyond the longitudinal center line of the conveyor as they move upwardly across the shovel plate. Accordingly the gathering devices 21 will be so adjusted that the arms of one of the devices move out of step with the arms of the other. To assure movement of the arms so that they always maintain the desired relative positions, it is preferable that the devices 21 be driven by the same power unit. Obviously the gathering and elevating conveyor devices may be driven by separate motors, or by a single motor through suitable drive means, and with the motor, if one is used, supported at any desired point on the apparatus as a whole.

Each gathering arm 31, as shown in Fig. 8, is provided with a gathering portion 37 having formed on its outer end penetrating points 38 for digging into the material to be loaded. Formed at approximately right angles to the gathering portion 37 is a portion 39 having an opening 41 through its inner end for receiving the pivot pin 30, and attached to the portion 39, as by welding, (or formed integrally if preferred) is a projecting portion 43 having a cam surface 44 which

acts to swing the arm in an improved manner, as hereinafter described. The arms 31 are mounted on the pivot pins 30, as shown in Fig. 6, so that their gathering portions 37 will extend substantially radially relative to the shaft 26 when the arms are in their inner positions, and their portions 39 extend generally tangentially to circles having their centers in the axis of the shaft. As the gathering devices 21 rotate, the arms 31 are swung outwardly about their pivot pins 30 during movement toward the forward end of the shovel plate so that the points 38 and the gathering portions 37 are forced into the material to be loaded. The arms are, moreover, held in their outward positions as they continue to move towards the conveyor in order that the gathering portions 37 may carry the material upwardly over the shovel plate onto the conveyor. When each arm reaches the forward end of the conveyor it is swung inwardly about its pivot pin 30 so as to move the gathering portion 37 transversely away from the conveyor and thereby release the material to be loaded. The arms are then held in their inner retracted positions until they again approach the forward end of the shovel. Desirably the rate of conveyor movement may equal or exceed the rate of movement of the points 38, at least when these overlie the edges of the conveyor. The swinging of the arms outwardly to their outer gathering positions is effected by a stationary cam element or portion 46 formed or mounted on the upper surface of the shovel plate 12 and provided with a cam surface 47 for engaging the portion 39 of the arms, which may be suitably curved as shown if desired. Each cam surface 47 extends, in the particular structure shown, spirally outwardly, to throw the arm out to digging position, then more or less concentrically with the hub adjacent it, to maintain the arm extended, and then slopes back slightly near its outer end. Another cam element or portion 48 formed on and projecting upwardly from the shovel plate is provided with a nose 48' and an inner cam surface 49 which is engaged by the cam surfaces 47 on the portions 43 formed on the arms after the nose 48' has forced the arms inwardly, to maintain the arms retracted. It will be noted that when the gathering arms are swung to their inner retracted positions the points 38 on the arms are the only parts projecting beyond the outer edges of the disk-like members 23, and in order to provide a clearance for the portions 48 on the shovel, notches 51 are cut in the ends of the arms beneath the points 38. This is of advantage for the reason, also, that it increases the clearance beneath the ends 38 as these move forwardly along the edge of the conveyor. In Fig. 9 there is shown a gathering arm like that of Fig. 8, except that it is provided with one or more pointed members 52 projecting upwardly from the portion 43 to aid in moving material to the conveyor.

The operation of the loading machine will be clearly understood from the description given. The machine illustrated is moved along the mine trackway to the material to be loaded and the front elevating conveyor 4 is then adjusted to locate its loading end in a position for gathering material. The chains 15 are then driven concurrently to move the scraper bars 19 orbitally upwardly over the plate 14 at the bottom of the conveyor and down again beneath the plate 14, and the chains 35 are driven to rotate the disk-like members 23 of the gathering mechanism 6 in opposite directions to cause the points 38 to ap-

proach the upper lip of the shovel plate in alternation. As the members 23 rotate, the gathering arms 31 are forced forwardly into the material due to engagement between the portions 39 of the arms and the cam portions 46 formed on the shovel plate. The gathering arms are held by the cam portions 46 in extended positions to carry the material over the shovel plate to the conveyor, but after each arm has been moved to a position where all the material ahead of it has been discharged onto the conveyor its portion 39 is moved out of engagement with the cam portion 46, and the cam portion 43 on the arm is moved into engagement with the nose 48' of the cam element or portion 48 on the shovel plate. Engagement between the portions 43 and 48' causes the arms to be swung abruptly about their pivot pins 30 away from the conveyor, thereby causing the ends 33 to move across above the lip at the front end of the conveyor 4 until their innermost position is reached. They then move, with the ends 38 only overhanging the sides of the conveyor trough, forwardly for a short distance, and then move on around arcuately until the position for their projection again is attained. As the scraper bars 19 move over the bottom plate 14 of the conveyor the material is picked up and carried to the rear conveyor 5 where it is conducted by any suitable means, like the conveyor 5, to a mine car or other suitable receptacle at the rear of the loading machine.

As a result of this invention it will be noted that an improved loading machine has been provided having improved gathering mechanism. It will further be noted that there has been provided an improved gathering device for a loading machine in which gathering members are moved into material gathering and discharging positions in an improved manner. As a more specific result of this invention, it will be noted that an improved gathering mechanism, providing for the movement of material onto a conveyor but operating so as not to pull any of the deposited material off of it, has been made available—one in which the motion of the gathering extremities laterally from extended position to a position close to the sides of the conveyor is at or below the point at which material is swept over onto the gathering conveyor. And the cams 48 serve to prevent the projections 43 from thrusting any material laterally. And the fact that the points 38 move no faster along the sides of the conveyor than the material moves upon the conveyor, also precludes dragging of material off the conveyor. It will further be evident that by the provision of the flexible gate between the shovel plate and the conveyor bottom plate, undesired escape of material from the conveyor is substantially reduced. These and other uses and advantages of the invention will be clearly apparent to those skilled in the art.

While there are in this application specifically described one form and a modification thereof which the invention may assume in practice, it will be understood that this form and modification are shown for purposes of illustration and that the invention may be further modified and embodied in various other forms without departing from the spirit or the scope of the appended claims.

What I claim as new and desire to secure by Letters Patent is:

1. In an apparatus of the character described, in combination, a rotating gathering head, a gathering arm pivotally connected to said gather-

ing head at a point adjacent its own leading end, said arm comprising angularly related inner and outer arm portions, said outer arm portion having a digging end, and stationary cam devices at opposite sides of the pivotal axis of said head, one of said cam devices nearer said axis than the other, said cam device nearer said head pivot axis being engageable by the inner arm portion to project and maintain in material-moving position said outer arm portion, and said inner arm portion having adjacent the arm pivot a projecting cam portion adapted to engage the stationary cam device which is more remote from said head pivot axis to swing said arm into retracted position and maintain it therein.

2. In an apparatus of the character described, a conveyor, a shovel plate having an edge over which material is moved onto the conveyor and a gathering device mounted on the shovel plate adjacent to but at one side of said edge, said gathering device having at least one arm pivotally mounted thereon, said arm having an outer digging portion and an inner, pivotally supported supporting portion, said outer portion having an end which in the projected position of said arm extends beyond the center line of said conveyor, cam means coacting with the inner side of said inner arm portion to swing the arm into digging position, and cam means including a stationary cam beyond the line of said edge, and a cooperating cam projection on the inner arm portion whose forward side is engageable with said stationary cam substantially as the outer arm portion reaches said edge, for moving said outer arm portion to the side of said conveyor to prevent its pulling material from said conveyor.

3. An apparatus as defined in claim 2 in which the profile of said cam projection and the orbit of the arm pivot are designed and constructed to move the outer arm portion transversely of said conveyor, substantially along the line of said edge, to the side of the conveyor.

4. In a loading mechanism, in combination, a movable frame, a conveyor means mounted on said frame for moving material to be loaded, a shovel portion on said frame at the receiving end of said conveyor means, and gathering means mounted on said shovel portion for moving material across said shovel portion and discharging it on said conveyor means, said gathering means comprising rotatable disk-like members mounted on said shovel portion for rotation about axes perpendicular to the upper surface of said shovel portion, gathering arms pivotally connected to the lower surfaces of said disk-like members at their outer edges and having material gathering portions extending substantially radially from said disk-like members, cam surfaces formed on opposite sides of said arms, and cam surfaces formed on said shovel portion and successively engageable by the cam surfaces on said arms for effecting movement of the gathering portions of said arms substantially radially of said disk-like members into material gathering and discharging positions.

5. A material gathering mechanism for a loading conveyor comprising, in combination, a rotatable member, gathering arms pivotally connected to said rotatable member at points spaced from its axis of rotation, said gathering arms having gathering portions extending substantially radially from said rotatable member and inner portions formed substantially perpendicular to said gathering portions, cam surfaces formed on opposite sides of said inner portions,

and means relative to which said rotatable member moves and which provides cam surfaces successively engageable by the cam surfaces on said inner arm portions for effecting swinging of said gathering arms into material gathering and discharging positions during rotation of said rotatable member, one of said last mentioned cam surfaces engageable by the cam surfaces at one side of said inner portions for moving said gathering arms into material gathering positions and another of said last mentioned cam surfaces engageable by the cam surfaces at the opposite side of the inner portions for moving said gathering arms into material discharge positions.

6. A material gathering mechanism for a loading conveyor comprising, in combination, a rotatable member, gathering arms each having one end pivotally connected to said rotatable member at a point spaced from the axis of rotation of the latter, each of said gathering arms having a gathering portion extending substantially radially from said rotatable member and a cam providing portion adjacent the pivoted end, oppositely directed cam surfaces on said cam providing portions, and cam members relative to which said gathering arms move and which are successively engageable by said cam surfaces for effecting a swinging of said gathering arms about their pivots, thereby moving said gathering portions into material gathering and discharging positions during rotation of said rotatable member.

7. A material gathering mechanism for a loading conveyor comprising, in combination, a rotatable member, gathering arms each having one end pivotally connected to said rotatable member at a point spaced from the axis of rotation of the latter, each of said gathering arms having a gathering portion extending substantially radially from said rotatable member and a plurality of cam portions adjacent its pivoted end, one of said cam portions extending outwardly from the arm and spaced from said gathering portion, material gathering means attached to said cam portion, and cam members relative to which said gathering arms move and which are engageable by said cam portions for effecting a swinging of said gathering arms about their pivots, thereby moving said gathering portions into material gathering and discharging positions during rotation of said rotatable member.

8. A material gathering mechanism for a loading conveyor comprising, in combination, a rotatable member, gathering arms each having one end pivotally connected to said rotatable member at a point spaced from the axis of rotation of the latter, each of said gathering arms having a gathering portion extending substantially radially from said rotatable member and a plurality of cam portions adjacent its pivoted end, one of said cam portions extending outwardly from the arm and spaced from said gathering portion, and cam members relative

to which said gathering arms move and which are engageable by said cam portions for effecting a swinging of said gathering arms about their pivots, thereby moving said gathering portions into material gathering and discharging positions during rotation of said rotatable member.

9. A material gathering mechanism for a loading conveyor comprising, in combination, a rotatable member, at least one arm pivotally connected at one end to said rotatable member, said arm having a gathering portion extending outwardly from said rotatable member and an inner portion formed at an angle with the gathering portion, a stationary cam surface curved outwardly in the direction of rotation of said rotatable member and engageable by one side of said inner arm portion for moving said arm outwardly toward a material gathering position, a cam projection formed on the other side of said inner arm portion, and a stationary cam member engageable by said cam projection when said inner arm portion is moved out of engagement with said outwardly curved cam surface for swinging said arm abruptly inwardly toward a material releasing position.

10. In an apparatus of the character described, a conveyor, a shovel plate having an edge over which material is moved onto said conveyor, and a gathering device mounted on said shovel plate for moving material across said shovel plate and discharging it on said conveyor, said gathering device comprising a rotating head, a plurality of arms pivotally connected to said rotating head, each of said arms comprising an outer gathering portion extending substantially radially from said head and an inner portion formed at an angle with said outer portion, cam means coacting with the inner side of said inner arm portion to swing the arm into material gathering position, and means including a stationary cam and a cam projection on the inner arm portion engageable with said stationary cam substantially as the gathering portion of the arm reaches said shovel plate edge for moving the arm away from said conveyor.

11. A material gathering mechanism for a loading conveyor comprising, in combination, a rotatable member, gathering arms each having one end pivotally connected to said rotatable member at a point spaced from the axis of rotation of the latter, each of said gathering arms having a gathering portion extending substantially radially from said rotatable member and a plurality of cam portions adjacent its pivoted end, and cam members relative to which said gathering arms move and which are successively engageable by said cam portions for effecting movement of the gathering portions of said arms substantially radially of said rotatable member into material gathering and discharging positions.

CARL J. WATNE.
